COUPLER

Neal Hudson, Phoenix, Ariz.

Application October 28, 1941, Serial No. 416,819

4 Claims. (Cl. 280—33.17)

This invention relates to couplers particularly adapted to couple tractors to farm implements, trailers and the like, and has for its objects—

First, to provide a coupler including a special type of tongue which will securely and automatically lock when the tongue is inserted in the coupler body and which may be unlocked by operated means contained within the coupler body, and controlled from any convenient place;

A second object is to provide a coupler where-in the movements between the drawing vehicle and the drawn vehicle may be accommodated both as to turning in a horizontal plane to a maximum angle as well as variations and angle between the vehicles in a vertical plane, all combined with a tongue having a swivel to permit relative twisting movement between the drawing vehicle and the drawn vehicle;

A further object is to provide a coupler having mechanism contained within an enclosed case which will receive and automatically latch and hold the draw bar of a tongue and retain the same until positive operation of mechanical mechanism releases the latching means.

Other objects will appear hereinafter.

I attain the foregoing objects by means of the construction and devices shown in the accompanying drawings, in which

Figure 1 is a plan view of the coupler;

Figure 2 is a side elevation thereof;

Figure 3, an end elevation thereof;

Figure 4, a plan view of the tongue, draw bar and swivel support therefor;

Figure 5, an elevation of the tongue, draw bar and support;

Figure 6, a sectional side elevation of the same;

Figure 7 is a plan view of the latch mechanism container body;

Figure 8, a side elevation thereof;

Figure 9, a mid-sectional side elevation of the complete coupler body showing the interior construction, drawn on a somewhat larger scale and substantially on line 9—9, Figure 7;

Figure 10 is a cross section thereof taken substantially on lines 10—10, Figure 9, drawn to the same scale as Figure 9;

Figure 11 is a perspective view of the coupler latch dog drawn on the same scale as Figure 9;

Figure 12 is a side elevation of the pneumatic plunger releasing device shown partially in section and drawn on the same scale;

Figure 13 is a perspective view of the latching plunger drawn on a somewhat smaller scale, and

Figure 14 is a perspective view of the combination latch dog release and plunger locking piece drawn on the same scale as Figure 13.

Similar numerals refer to similar parts in the several views.

The latch mechanism is enclosed in a case or shell 2 composed of upper and lower halves in-

dicated by numerals 3 and 4 respectively, held together by bolts 5 and 8. This shell has a general spherical body portion, the interior of which is substantially spherical so that the inner latch holding body 7 may pivot on a vertical axis within the shell. The latch body, shown particularly in Figures 7 and 8, is generally spherical except that it is truncated slightly at the top and more substantially at the bottom as indicated by numeral 9. Annular V-shaped grooves 10 and 11 are turned around this spherical body near its top and bottom respectively. These grooves form bearing-like annular channels and are constructed so that they are circular and are generated so that the entire sphere will turn within the case 2 on a vertical axis as indicated at x—x, Figure 8. The interior or case 2 is provided with annular guide ribs setting in these grooves.

Near the rear edge of each of the case halves 20 these guides 14 and 15, respectively, are provided with annular walls having a V section. The upper wall 16 is on a plane at right angles to the axis of pivot and the other wall 17 on an annular sheath corresponding to a projection of the radius of the sphere. This construction provides an additional means for holding the upper and lower parts of the case together when the device is under strain. These grooves extend approximately ten degrees on either side of the longitudinal center of the shell parts. For the rest of the circumference these guides consist of a lower face 18 at right angles to the axis of pivot and a vertical annular side wall 19. This construction is necessary to permit the assembling of the body 7 within the two case halves. This combination provides a semi-spherical body 7 within the two case halves which will turn therein on a vertical axis corresponding to the center of the spherical body and the spherical case. The annular guides act as bearing surfaces and the portion of the guides having the wedged shaped section at the rear edges along the rear portion of the mount of the containing case act as retention means to hold the rear portion of the case halves together.

A rectangular opening 20 is cut into the rear face of the latch body 7 and the walls of this opening generally converge toward the center. This opening is sized in proportion to receive the tongue D stirrup 21 and the side walls converge at a slant generally proportionate to the angular pitch of the side bars 22 of the latch, whereas the upper and lower faces of this opening are sufficiently large to permit an upward and downward play of the D stirrup within the opening when its draw bar 23 is locked in place within the opening. This lower face may be formed of a removable block 25, as shown in Figure 3 and indicated by dotted lines in Figure 9. This construction may be used to afford replacement after

wear, and facilitate assembly of the parts within body 7. This lower face has a raised central portion 26 forming a lower retaining lip; its inner face 27 being shaped to conform to the circumference of the cross bar 23. The latch body is provided with a vertically extending rectangular shaped opening 30 which may be termed a well, extending entirely through it. The central portion of this opening is enlarged at the rear, indicated by 31, to accommodate certain spring latches hereinafter described, and a centrally positioned opening 32 extends forward across the top and down into the body to accommodate the main latch 33.

Within these openings the working parts of the latching mechanism are situated. Of first importance is main latch 33 which rocks in an arcuate channel 35 (as viewed in vertical section in Figure 9) upon a transverse shaft 36. In Figure 9, the latch is shown in closed or latched position; to open it rocks counterclockwise. It normally assumes the closed position by reason of its center of gravity being to the rear of its axis of support on shaft 36. The limits of its motion being indicated by the dotted outlines 37. This latch is made of cast or forged steel generally in the shape shown and the general outer surfaces may be machined to exact shape. However, the only necessary machining is that of the semi-circular rocking surface 38. At the rear of this latch there is a butting face 39 angularly disposed so as to contact and be stopped definitely by engagement with a similar butting face 44 on the latch dog 40. The forward bottom surface is shaped to form a hook 133 conforming to the surface of draw bar 23 and adapted to engage this draw bar when inserted into the rectangular opening 20.

Second in importance is latch dog 40 which pivots on a transverse shaft 41 extending through the latch housing. Its center of gravity is forward of its axis of pivot so that it normally assumes the locked position as indicated by solid lines in Figure 9. This dog has a peculiar shape particularly adapted to the use here concerned and is therefore shown in perspective in Figure 11. It may be made of cast steel or forged steel and machined on the working surfaces hereinafter described. A transverse bearing hole 42 is positioned near the rear bottom portion of the dog body. Below and forward of this is a transverse lifting lug 43 adapted to contact the dog lifter hereinafter described. The lower edge of the dog is shaped to provide an arcuate surface relative to axis of shaft 41. The upper and rear portion of its surface extends forward arcuately but its exact contour is not critical. Along the forward upper edge is a butting surface 44 formed and disposed at an angle to contact the corresponding butting surface 39 on latch 33. The angle of the plane of contact between these surfaces is such that when the dog is rotated counter-clockwise, as in releasing movement, there will be little hang or friction on the lower edge of this surface. Below this butting surface there is a latch notch 45 extending transversely and having its lower side set at an angle to correspond to the position of butting face 39 of latch 33 when the latch is in opened position and the dog is rotated to opening position as indicated by dotted outlines 46. On each outer face of the latch there are outwardly extending ears or lugs 47 adapted to engage shoulder blocks 47a set in either side of upper side walls of well 30 in the latch body. Engagement of the lower surfaces

of these lug ears takes the strain of the rocking of the dog somewhat off of its transverse bearing shaft 41. Within the rear arcuate surface 48 of the dog there are three latching holes to receive spring setting latches sears. These are indicated by numerals 49, 50 and 51. The center portion of the upper edge of the latch is cut away at 52 to provide clearance for a spring latch push rod hereinafter described.

While both the latch and latch dog normally assume closed position by gravity it is to be understood that this may be enhanced by loop springs surrounding their respective supporting shafts and operative between the case body and the latch and dog bodies respectively.

To rotate latch dog 40 from open to closed position a dog lifter 60 is positioned in well 30 and shaped to freely move up and down therein. This lifter has a flat transverse portion 61 at the ends to downwardly depending legs 62. Thus it has an inverted U-shape.

Within the span or open space between these legs the rear end of the jam plunger 66 works freely, having a longitudinal horizontal motion. This space is of sufficient width to span or bridge the rear flat portion of this plunger. The plunger works longitudinally by sliding motion within the lower part of the well and a forward extension thereof 67 in the lower portion of the latch body 7. Upward motion of the latch dog lifter is obtained and actuated by a hydraulic piston 71a working in cylinder 18. This cylinder is set on a plate 71 attached to the flat bottom 74 of body 7 and is sized so that it extends up through an opening 67 in the rear flat portion of plunger 66 and the piston 71a is proportioned so as to reach and bear on the underside 64 of the flat top portion 61 of dog release or lifter 60. This piston is actuated by fluid forced under pressure through an orifice 72 in block 71 and thence through a union coupler 73 axially positioned relative to the bottom face 74 of body 7 and thence connecting through a flexible metal tube 75 positioned in a drilled opening in the lower shell half 4 to a source of oil pressure controllable through any suitable valve. Two springs symmetrically positioned on each side of the flat portion 68 of plunger 66 and marked 78 operate plungers 77 pushing against the back wall of well opening 31 so as to normally force plunger 66 forward to the forward face 69 of the opening 67. Of these parts just described, the latch and latch dog form the general latching mechanism. The latch dog lifter and hydraulic piston form the unlatching mechanism and plunger 66 is the main part for releasing the unlatching mechanism.

In addition to these parts there are three spring latches used to hold these main parts in latched and unlatched positions throughout the cycle of operations. Reference is made to Figure 10. This shows the face of well opening 31 to which these spring latches are attached. At the extreme right, as viewed in this figure, 89 indicates the open-position latch. This latch is pivoted at the top on studs 81 set into the back wall of well opening 31, and extends downwardly so as to engage the rear face of extension 68 of plunger 66 at 82. The latch is resiliently held forward by a plunger and spring 83 set into the back wall of well portion 31. This plunger is not shown in Figure 9 because it is directly behind a plunger 93 hereinafter described. The forward face of spring latch 80 is provided with two latch sears. An upper sear 84 is adapted to en-

gage hole 49 in latch dog 40 to hold it in open position by contact with the lower edge of this opening. A lower sear 85 is positioned to engage a notch 86 in dog lifter 60 when it is in raised position. In the center of well opening 31 a secondary open position spring latch 99 is pivoted on bearing stud 91 at its bottom. This latch is held resiliently forward by a spring and plunger 93 set in the back wall portion of body 7. At the top it is hinged at 94 to a push rod 95 which extends forward sufficiently to engage a stop lug 96 on the top of the upper portion of latch 33. Sear 97 extends forward from the forward face of this latch and is positioned to engage the hole 50 on the rear of latch dog 40 and retain it in unlatched or open position by contact with its bottom face. A third spring latch 100 is supported at its top on stud 101 in the back wall of well 31. It is urged forward by a plunger 103a and spring 102 set in the same wall and is provided with a sear 103 positioned to engage hole 51 in the rear of latch dog 40 to hold the latch dog in closed or latched position by contact with the top face of said opening. The lower portion is provided with a slide surface 104 spaced and positioned to engage the rear face of the upper portion 61 of latch dog release 60 as it moves upward.

Spring latches 99 and 100 may thus be known as mechanism for releasably retaining the main latching mechanism in open or unlatched position. Spring latch 100 constitutes an additional latch locking mechanism.

The two rearwardly diverging side bars 22 connected at the front by tongue draw bar 23 and by the fork 123 at the rear constitute the drawbar D stirrup. The fork 123 is welded to or otherwise attached to a cylindrical plug 124 having an annular groove 125. A two part sleeve clamp 126 encloses the end of tubular tongue bar 127 attached to the vehicle to be drawn. Lugs 128 extending inwardly from the halves of the two part sleeve clamp 127 through holes in the tongue bar end, extend into annular groove 125 and form a solid means for retaining the plug and permitting axial movement between the D stirrup and the tongue bar.

The forward end of the coupler case is attached to the tractive vehicle by a large eye ring 130. Since the coupler latch body 7 pivots within case 2 the adjacent edges of the upper and lower halves of the case are cut away at the rear and sides to form a semi-annular slots 131 to give the tongue free vertical swing within the coupler body at whatever angle this opening may bear to the longitudinal axis, or line of traction of the coupler case. Thus coupler body 7 may pivot within case 2 to an extreme of ninety degrees on each side of the longitudinal center. At any pivotal position tongue D stirrup has a free vertical swing of approximately forty-five degrees.

Use and operation

It is intended that this coupler be used in conjunction with a tractor vehicle with the latch body shell 2 set into the rear of the vehicle and the tongue and draw bar attached to the appliance or vehicle to be drawn. Coupling is completed and backing the tractor so that the coupler body 7 is directed toward the draw bar stirrup 21. If the parts are substantially aligned it is only necessary to bring the parts together, whereupon the draw bar stirrup will be received into the opening 20 of the latch body. If the

parts are not aligned it is a simple matter to turn the latch body 7 within the case so that the opening substantially faces the draw bar stirrup. Rear motion of the tractor so as to force the draw bar stirrup into the rectangular conical opening in the latch body causes the draw bar 23 to be engaged between the raised retaining portion 27 on the lower face 25 of the opening and the latch 33 which is held in latched position by the mechanism hereinabove described. Release of the latching mechanism is effected by the injection of oil under pressure through tube 75 to cylinder 70, whereupon a series of operations of the parts contained within body 7 takes place to effect a release of latch 33 from the closed position and permit the withdrawal of the D stirrup latch bar 23.

Operation of the inner working portions of the latch body is explained as follows: Commencing with the closed position, as shown in Figure 9, with the tongue draw bar 23 in position as indicated, piston 71a moves upward, forcing the dog release 60 to the upper limit of its travel indicated by dotted outline 60-A. The upper face of portion 61 of this part engages the lower lug 43 of latch dog 40, moves it upward and causes the dog to swing on its bearing 41 in a counterclockwise direction as indicated by dotted outline 46. On its upward travel the rear face of dog release 60 engages the portion 104 of spring latch 100 forcing it to the rear and disengaging sear 103 from opening 51 in the latch dog. Thus, the counterclockwise motion indicated can take place. Motion of the latch dog to this open position indicated by 46 releases the butting surfaces 39 and 44 from the closed position, whereupon latch 33 is free to rock on its semi-bearing support 38 on transverse rod 36 to the open position indicated by the dotted outline 37. As the tongue draw bar 23 is removed, it rides up over the raised portion 27 and pushes latch 33 to the open position 37.

Concurrently with the upward motion of dog release 60 by piston 71a it is held and retained in position by engagement of spring latch sear 85 in notch 86 and dog 40 is retained in open position by the engagement of spring latch sear 97 in hole 50 and spring latch sear 85 in hole 50 and spring latch sear 85 in hole 49 in the latch dog.

The withdrawal of the D stirrup cross bar 23, moving latch 33 to the open position causes the stop lug 96 to engage push bar 95 and this, in turn, moves spring latch 99 to the rear, causing the opening latch sear 97 to disengage from hole 50, whereupon the unbalanced forward weight of latch dog 40 causes it to move slightly forward but its forward motion is stopped by engagement of sear 84 on spring latch 80 with the bottom of hole 49, thus, after the withdrawal of D stirrup the latch dog is retained only by sear 84 and is ready to close upon a second movement of latch 33 to the opened position by a re-entry of D stirrup draw bar.

Two latch dog retaining sears and spring latches are used to prevent a full release of the latch dog due to any accidental failure of the working parts, or an unintentional operation of plunger 66 while uncoupling.

Upon recoupling the first motion of the entrance of the draw bar 23 of the D stirrup moves the latch 33 to the open position but does not release latch dog 40 until the draw bar 23 is moved hard against the forward face 166 of plunger 66, whereupon this plunger moves to

the rear, as indicated by dotted lines, against the tension of springs 78 and in doing this, moves spring latch bar 80 to the rear, whereupon sear 84 releases latch dog 40 and at the same time sear 85 releases dog lifter 60. This latter drops of its own weight to the closed position. As soon as draw bar 23 is moved to the rear again, as in the forward motion of the tractor plunger 66 moves to the rear and dog lifter 60 no longer being supported on shelf 167 may drop to lowered position. During the time the dog lifter was retained in its upper position, plunger 66 is free to move to the rear because of the shelf notch 167, being positioned to slide under the lower face 64 of the lifter 60. After sear 85 disengages from notch 86 and lifter 60 is ready to fall rearward motion of plunger 66 slides the under face 64 on shelf 167, thereupon when the lifter 60 drops further forward motion of plunger 66 is blocked by the face 169 of this plunger. Thereupon, the cross bar 23 is fully locked in tractive position. It can not move rearward because of the engagement of the latch 33 which is held in position by latch dog 40, as above described. Further, latch dog 40 is held in the latched position by the engagement of the spring latch sear 103 with the opening 51 in the latch dog body. Draw bar can not move forward because of engagement with the forward face 166 of plunger 66, and plunger 66 is, in turn, locked in its rearmost position by the engagement of vertical shelf face 168 with the rear face of latch dog lifter 60.

I claim:

1. A coupler operative between tractive and drawn vehicles comprising a coupler case adapted to attachment to a tractive vehicle, a coupler body adapted to turn on a horizontal pivot therein, a rectangular tongue receiving cavity therein having inwardly converging sides, the lower face thereof having a draw bar retaining lip, a rocking latch operative in the upper face thereof, a latch dog positioned within said coupler body adapted to hold said latch in latching position engaging a draw bar of a D stirrup on a tongue, mechanism within said latch body for releasing said latch from said holding position to a released free position, said mechanism being adapted to control from outside said coupler case, together with a tongue attached to a drawn vehicle having a D stirrup provided with a transverse draw bar attached by a swivel connection thereto, the sides of said D stirrup diverging rearward to substantially conform to the sides of the rectangular opening in said coupled body and said draw bar adapted to engage within said opening between the lip on the lower face of said opening and said latch to be retained therein.

2. A coupler operative between tractive and drawn vehicles comprising, a coupler case adapted to be attached to a tractive vehicle, having a semi-spherical shell, a semi-spherical latch body turnable therein on a vertical axis, mechanism within said latch body adapted to releasably engage a transverse draw bar of a tongue D stirrup, said case being formed to enable said latch body to turn on its vertical axis throughout approximately one hundred eighty degrees while said tongue is engaged.

3. In a coupler, as herein disclosed, latching

mechanism adapted to releasably latch a transverse draw bar formed at the forward portion of a D stirrup tongue body, including, in combination, a shell composed of upper and lower halves, having internally extending annular bearing guides positioned in horizontal planes within the upper and lower parts thereof, with the rear and side central portion cut away forming an arcuate horizontal slot, a semi-spherical latch body adapted to fit within said case body and turn therein on a vertical axis having annular grooves in its upper and lower portions cooperative with said guides in said case, and a rectangular tongue opening in the rear face thereof having its sides and top and bottom faces inwardly converging, a vertical well opening extending through said body opening into said tongue opening, a rocking latch operative in an opening adjacent said well on a transverse supporting shaft, and having a hook on its rear lower portion adapted to engage the upper portion of a transverse tongue draw bar, a retaining lip on the lower face of said rectangular tongue opening adapted to partially engage the lower portion of a transverse tongue draw bar, a latch dog pivotally mounted within said well adapted to hold said latch in latched position and to swing to released position whereby said latch may raise to released position, mechanism for moving said latch dog to latch released position, including a dog lifter, a hydraulic elevating piston controlled by oil pressure from outside said coupler, and spring latch mechanism for retaining said latch dog and latch dog lifter in released position after the lifting operation of said elevator, together with mechanism for releasing said latch dog from open released position including a plunger having a face positioned at the rear of the rectangular opening in said latch body and adapted to contact the draw bar of said D stirrup forming a forward stop therefor and positioned to operably contact said spring latch retaining mechanism when pressed forward by said draw bar, and to be locked in its rearmost position by said latch dog lifter when said lifter is in its lowered position.

4. In a coupler for tractive and drawn vehicles, latching mechanism adapted to releasably latch a tongue draw bar including, a latch body horizontally pivotally supported in a case, a rectangular opening in said latch body having converging sides and top and bottom faces adapted to receive a tongue end including a transverse draw bar, mechanism for retaining said draw bar including a retaining lip on the lower face of said opening and a latch having a rocking motion operable within the upper face of said opening, locking mechanism for retaining said latch in locked position, opening mechanism for releasing said locking mechanism from locked position and retaining means for releasably holding said opening mechanism in open position, and tripping mechanism for releasing said opening mechanism from opened position including a plunger operated by said draw bar, whereby insertion of said draw bar into said opening will trip and release the mechanism holding the latch in unlocked position and said latch will assume a closed and locked position.

NEAL HUDSON.
